UNITED STATES PATENT OFFICE.

FREDERICK W. MATTHIESSEN, OF LASALLE, ILLINOIS.

PROCESS OF MAKING PRODUCER-GAS.

SPECIFICATION forming part of Letters Patent No. 730,941, dated June 16, 1903.

Application filed October 29, 1902. Serial No. 129,215. (No specimens.)

To all whom it may concern:

Be it known that I, FREDERICK W. MATTHIESSEN, of Lasalle, in the State of Illinois, have invented a certain new and useful Improvement in Processes for the Manufacture of Producer-Gas, of which the following is a specification.

My invention relates to the burning of coal or its equivalent for the production of producer-gas and other purposes without the escape of smoke.

A prior process for the smokeless combustion of fuel consists in first igniting a charge of fuel in a chamber of considerable length and permitting it to burn by natural draft until the combustion of the entire fuel column has commenced, after which the chamber is closed and currents of air are passed transversely through perforations in the chamber and through the fuel column as it is consumed and progresses through the chamber and further on in the length of the chamber returning the gaseous products with additional air through other perforations in the chamber transversely through a portion of the fuel which has previously been treated and partly consumed and repeating this operation of returning the products of combustion with air, &c., until the fuel is converted into combustible gas which does not precipitate carbon.

My invention is distinguished from the prior one in first distilling the hydrocarbons from the fuel by heat reflected upon it without air-currents being passed through it and in not directly mixing the gaseous products of combustion with additional air outside of the fuel-chamber. I attain the desired results by subjecting coal or its equivalent under confinement in a suitable chamber to sufficient heat reflected upon it without air-currents passing through it to distil the hydrocarbons and to oxidize both components thereof in the chamber above the coal and thereafter pass the coke formed in the distilling process to the lower part of the chamber and burn the same there with oxygen which may be in excess of the gases produced in the upper part of the chamber and with oxygen in fresh air specially introduced in or through the coke for that purpose, thus making two distinct steps in the process of com-

bustion, the admission of air in the first step to be so regulated that no solid carbon particles, smoke, or soot results from the burning of the hydrocarbons. No smoke or soot can form in the second step, since carbon without combination is not volatile.

The process consists in separating by distillation in a gas-producer chamber the volatile parts of a fuel from the non-volatile parts and in oxidizing the volatile parts as a first step and the non-volatile parts as a second step in the operation.

The process may be carried out by means of an apparatus constructed as illustrated in the accompanying drawings, in which—

Figure 1 is a vertical central section of the apparatus. Fig. 2 is a top or plan view of the same with portions of the top broken away to show the interior construction and having the exit-flue removed. Fig. 3 is a detail showing a detached part in perspective.

In the drawings, A is a chamber mounted on a bottom plate A', having brackets a.

B is a flange or extended bottom of an enlarged part of the chamber, and C the chamber-cover, which forms a gas-tight connection over the chamber. The cover is provided with openings a', through which twyers from an air-pipe a² are introduced for forcing air into the enlarged upper part of the chamber.

D is a flue for taking off the gas, and it communicates with the lower part of the chamber.

The twyers are provided with valves a³ for regulating the admission of air, so that all the elements of the hydrocarbons can be oxidized in the enlarged upper part of the chamber before the mixing with the fuel-gases from the coke burning in the central lower part of the chamber.

E is an upright shaft which is stepped at the bottom in a bearing of the frame E' and at the top in a bearing E². The bottom plate A', mounted on the shaft, supports the chamber so as to permit it to revolve. The part of the flue D within the chamber is also connected with the shaft by radial flanges d. The cover is stationary and supported independently of the chamber by a frame F, resting on uprights F'.

G is a stationary casing having perforations g for the admission of air to the bottom of the chamber. The connections at e are made gas-

tight by means of a water seal of ordinary form. The cover is provided with an oblong opening over the enlarged part of the chamber, and through this opening the spout H of the feed-hopper is inserted. The inner end of the spout is shortened at one side, as shown at h, and inserted until the longer side h' will just clear the flange B. Stoking-openings c' are also provided, but ordinarily kept closed.

10 A minute opening into the chamber at c² or other suitable place is provided through which a sufficient jet of gas to support a pilot-flame will issue.

H' is a plowshare-like scraper mounted on the spout and adapted to throw the coal from the flange B toward the center of the chamber.

I is a cone on the shaft and causes the ashes and clinkers to be deflected out toward the 20 margin of the plate A'.

J is a scraper mounted on the casing and extended obliquely across the margin of the base-plate A' outside the base of the cone, so as to sweep the ashes and clinkers out through 25 an extension G' of the casing into an ash-receptacle G², forming a water seal with the lower edge g' of the extension.

K is an annular rack connected with the bottom of the base-plate and adapted to engage a pinion k of a power-shaft for rotating the chamber.

In the operation of the process when using the described apparatus coal is fed continuously to the upper part of the chamber and 35 retained there until hydrocarbons are distilled by the heat produced by the burning of the hydrocarbons themselves in the upper part of the chamber. Sufficient air is admitted over the coal to burn the hydrocarbons to producer-gas. A surplus of oxygen over and above the amount required for that 40 purpose may be introduced. By the rotation the coke is passed to the central lower part of the chamber and burned there with the

surplus atmospheric oxygen introduced to the 45 hydrocarbons and with sufficient further air admitted under the coke to burn the same fully. In this instance distillation and oxidation of the hydrocarbons in the upper part of the chamber are comprised in the first step 50 of the process, and the burning of the coke in the central lower part of the chamber with the surplus of oxygen from the gases resulting from the first step and with the further oxygen in the fresh air introduced under the 55 coke constitutes the second step. The test as to the sufficiency of air admitted over the coal may be determined by the small pilot-flame on the chamber or by the absence of smoke at the exhaust.

60 What is claimed is—

1. The process of making producer-gas, which consists in separating, by distillation in the upper part of a chamber, the volatile parts of a fuel from the non-volatile parts by 65 heat reflected upon the fuel and oxidizing the volatile parts in the upper part of the chamber as a first step in the operation, and passing the non-volatile parts of the fuel to the lower part of the chamber and oxidizing 70 them as a second step in the operation as specified.

2. The process of making producer-gas, which consists first in subjecting coal under confinement in one part of a chamber to sufficient reflected heat absent from air-currents passing through the fuel to distil the hydrocarbons of the coal and oxidize both components of the hydrocarbons to producer-gas by air admitted over the coal, and second in 75 oxidizing to producer-gas in the lower part of the chamber the coke produced in the first step of the operation by currents of fresh air introduced to the coke as specified.
